UNITED STATES PATENT OFFICE.

EDWARD PHILIP KECK, OF CLEVELAND, OHIO, ASSIGNOR TO ARTHUR S. GILMAN, OF CLEVELAND, OHIO.

CARBON-PAPER FEEDING DEVICE FOR DUPLICATING TYPEWRITING MACHINES.

Application filed July 19, 1923. Serial No. 652,509.

To all whom it may concern:

Be it known that I, EDWARD PHILIP KECK, a citizen of the United States, resident of Cleveland, county of Cuyahoga, and State of Ohio, have invented new and useful Improvements in Carbon-Paper Feeding Devices for Duplicating Typewriting Machines, of which the following is a specification, the principle of the invention being 5 herein explained, and the best mode in which I have contemplated applying that principle, so as to distinguish it from other inventions.

My invention relates to carbon paper feeding devices for duplicating typewriting machines, its object being to provide means for feeding and manipulating the carbon-sheets used for making manifold impressions upon manifold forms.

20 The said invention consists of means herein fully described and particularly set forth in the claims.

More specifically, my invention consists of a modification of the devices shown and 25 described and claimed in pending application Serial No. 634,696, filed April 26, 1923, by Arthur S. Gilman, the method of manipulating manifold forms and carbon-sheets by means of the present invention, being generally the same as that described 30 and claimed in said above mentioned application.

The annexed drawings and the following description set forth in detail certain means 35 embodying my invention, the disclosed means, however, constituting but one of the various mechanical forms to which the principle of my invention may be applied.

In the said annexed drawings:

40 Figure 1 represents a front elevation of the device embodying my invention, showing same attached to the platen-carriage of a typewriter, of which latter only a fragmentary portion is shown.

45 Fig. 2 represents a side elevation of said device attached to such platen-carriage.

Fig. 3 represents a vertical transverse section of the device and taken upon the planes indicated by lines III—III, Fig. 1.

50 Fig. 4 represents a detailed section taken upon the plane indicated by line IV—IV, Fig. 2.

Figs. 5 and 6 represent sections taken respectively upon the planes indicated by 55 lines V—V, Fig. 4.

Fig. 7 represents a transverse section taken upon the plane upon line VII—VII in Fig. 2.

Fig. 8 represents a transverse detailed section taken upon the plane indicated by 60 line VIII—VIII in Fig. 2.

Fig. 9 represents a plan of one of the carbon-sheet guides showing a carbon-sheet threaded therethrough.

The disclosed embodiment of my invention is designed to receive a manifold form of five parts or less and includes an upright frame 1, which is of a form adapted to be attached to the platen-carriage 2 of a typewriting machine, such attachment being 70 made in any convenient or suitable manner. This frame, as illustrated, is shown to consist of two side members 3—3, a bottom member 4, cross or brace members 5—5, and a top transverse member 6 which acts as a 75 guide for leading continuous forms 7 from the source of supply upwardly and then over and downwardly to the typewriter platen 8 as shown in Fig. 3. This source of supply (not shown) may be a multiplicity of rolls of forms; may be a box of what is known as "fanfold" forms, the latter being the term used in the trade to designate forms folded transversely and longitudinally, or may be a box of forms such as are 80 shown, described and claimed in U. S. Patent No. 1,368,929, issued Feb. 15, 1921, to The A. S. Gilman Printing Company. The front and back of this member 6 are downwardly curved as shown at 9—9.

The front portion of the frame 1 is preferably inclined slightly toward the rear as shown in Fig. 2.

Secured to and projecting laterally from the said front portion of each of the side members 3 of the frame, are two brackets 95 10 provided with bearings 11—11, Fig. 4. In these bearings there are mounted the journals 12—12 of a spindle 13. To one end of this spindle is fixedly secured a detent wheel 14 which is engaged by a detent 14' which may be thrown into or out of engagement with such detent wheel at will, the said detent being so arranged that when thrown out of engagement it may remain so until manually restored.

The other end of the spindle is threaded as at 15 and upon this threaded portion is mounted a square nut 16. This nut projects into the squared end 17 of a central 100 105 110

bors 18 and carbon-sheet roll 19, Fig. 4. Surrounding the interior portion of the spindle 13 is a helical spring 20 one end of which is secured to the roll 19 as at 22 in any suitable or well-known manner. Engaging the threaded portion of the spindle 15 and outwardly beyond the nut 16 is a stop nut 23 which is locked in place by a lock nut 24.

10 The brackets 10—10 and other bearings are so arranged that the axis of said spindle is parallel with the inclined front face of the supporting frame 1, as shown in Fig. 2.

15 Fig. 4, as will be noted, is an axial section of the left-hand roll as viewed from Fig. 1, and the thread on the portion 15 of this spindle is a left-hand thread. Two carbon sheets 25 are wound upon this left-hand roll 19 so as to unwind therefrom in a clockwise direction, so that in unwinding it may be led from the top of the roll over toward the center of the supporting frame.

20 The thread of the right-hand roll, however, is a right-hand thread, and the two carbon-sheets 25 which are wound thereon unroll in a counter-clock-wise direction and may also be led from the top over toward the center of said frame.

25 30 The construction of the two rolls, therefore, is identical with the exception of the direction of the threads of the spindles and the nuts.

35 The helical springs 20 are so wound that when the carbon-sheets are unwound over the rolls, the said springs will oppose the unwinding so that when the carbon-sheets are released the rolls will automatically wind the latter in.

40 45 The spindles 13 furthermore are each provided with an interior shoulder 26 which prevents longitudinal displacement of the roll on its spindle.

45 Formed integrally with and projecting inwardly from each of the two side members 3—3 are two lugs 27—27 and 28—28, Fig. 1. Each of these lugs carries a fixed stud 29 which projects perpendicularly with reference to the plane of the front face of the 50 device. These studs have their outer ends threaded as shown in Fig. 8 and have their axes located so as to pass through the corners of an imaginary rectangle.

55 The top surfaces of the lugs 27 line in a plane parallel with the direction of feed of the forms downwardly into the platen-roller.

60 Upon these studs are removably secured a multiplicity of carbon sheet guides 30, four in the case illustrated, two on the left-hand pair of studs and two on the right-hand pair. The two on the left-hand pair project laterally to the right and the two on the right-hand pair project laterally to the 65 left. These guides are supported solely on

one end of these studs so that their other ends are free as shown in Figs. 7 and 8. By such construction the guides may be interleaved with the manifold forms, the alternate lateral edges of which are attached to each other as in the case of the "fanfold" forms. A cross section of such a "fanfold" form when extended is shown at 31 in Fig. 2. For this purpose, the guides project right and left alternately from the 75 studs.

Each guide 30 is provided with a slot 32, Fig. 9, which forms a guiding surface 33 at an angle of forty-five degrees with reference to the direction of feed of the form 80 and the slots on the succeeding guides at right angles with each other.

85 The supported ends of the guides are each formed with two pairs of holes 34—34, by means of which they may be slipped on the 90 studs 29. By providing these pairs of holes, the guides may be adjusted to assume different positions laterally whereby they may be adapted to conform with different widths of manifold forms. As illustrated in Fig. 1, 95 the adjustment is such as is required for a given form, whose width is equal to the transverse distance between the fore ends of two succeeding guides 30. By shifting one 100 of the sets of guides, so as to cause the studs to engage the other set of holes thereon, it will be seen that the guides may be used in connection with a manifold form of a greater width. By then shifting the other set of guides so that the stud will engage 105 its second pair of holes, a still wider manifold form may be used in connection with the device, all as will be readily understood by those skilled in the art. While but two sets of holes are provided in the form of device shown, it will be obvious that additional holes may be provided as may be required by forms of still different widths.

110 Thumb nuts 35 are provided as shown in Figs. 7 and 8 to secure the guides to place.

115 In preparing the above described mechanism for use, the detents 14' are first disengaged, whereupon the carbon sheets are unrolled by hand and threaded respectively through slots 32 of the carbon-sheet guides 30, one carbon-sheet passing through but a single slot. In the specific mechanism shown, Figs. 7 and 8, the uppermost carbon-sheet of the right-hand roll is threaded through the slot of the uppermost right-hand guide and then led downwardly to the platen-roller. The uppermost carbon-sheet of the left-hand roll is then threaded through the slot of the next guide, led downwardly, the second sheet of the right-hand roll is then led through the third guide, and finally the second sheet of the left-hand roll passed through the slot of the last guide and also led downwardly.

120 125 130 The manifold form strip 9 is then led over

the member 6 passed downwardly with its successive forms, with the exception of the upper and lowermost thereof, passing between the guides and carbon-sheets, so as to 5 inter-leave the latter with such forms and allow a carbon-sheet therefor to lie between each two successive parts of the manifold form as shown in Figs. 3 and 7.

The detents are now caused to engage 10 the detent wheels 14 and the manifold-form strip and the inter-leaved carbons may then be passed through the platen-roller of the type-writing machine and the necessary type-writing placed thereon by such machine. 15 After the regular typewritten matter is produced, the platen-roller is reversed so as to carry the typewritten forms and carbons back. This reversal is continued, as in the case of the device of the above mentioned 20 application until the carbon-sheets are released from between the platen-roller 8 and the pressure roller 36. During such reversal, the rolls will automatically "wind in" the carbon-sheets as will be noticed from the 25 previously described construction of such roll until the nut 16 strikes the stop nut 23. The nut 23 is so adjusted that when it is struck by nut 16, the ends of the carbon-sheets will have been released from between 30 the platen and pressure rollers. The platen-roller is then operated to carry the manifold sheets forward, during which operation the carbon-sheets will remain stationary. Such movement of the platen-roller is continued 35 until the sheets reach the line at which it is desired to tear them off. This tearing off is accomplished by the usual tearing-off knife 37 which is attached transversely to the frame 1 and in its regular position, all 40 as will be readily understood.

The above operation is continued until those portions of the carbon-sheet which have been used, are worn out.

After the wearing out of the portions of 45 the carbon-sheets mentioned, such portions are torn off, and such tearing off is accomplished in the following manner:

After the completion of the last type-writing operation before the tearing-off is 50 effected, the forms and carbons are backed up as previously described until the carbons are released. The detents 14' are then disengaged. The forms and carbons being then grasped by the fingers so as to pinch them, the platen-roller is then rotated to carry 55 both forms and carbons forward and around the platen-roller. This operation is continued until the extreme ends of the carbon come within a required distance from the 60 knife 37 which is about $\frac{3}{4}$ inch.

The detents are then re-engaged and the rotation continued until the tearing-off line is reached, whereupon the forms and carbons are torn off. The forms and carbons are 65 then backed up until they become disengaged

from the platen and pressure rollers. At the moment of such disengagement, the nut 16 will not have reached the stop 23 and a small amount of tension will remain in the coil springs 20 which will cause a continuation of 70 the winding in of the carbons, and their ends to be removed from the extreme ends of the manifold form, thereby leaving the required space between such carbon and form ends for properly manipulating same as is the case 75 of the mechanism of the above mentioned application.

What I claim is:

1. In a device of the class described, the combination of means for guiding a plurality 80 of manifold forms and mounted upon the platen-carriage of a typewriting machine; a carbon-roll mounted upon said guiding means laterally thereof, and having its axis extending in the direction of feed of said forms, a carbon-sheet guide having one end secured to the form-guide frame; said carbon-sheet guide having a guiding surface extending at an angle of forty-five degrees, with reference to the direction of travel of 85 said forms, whereby the carbon-sheet from said roll may be fed in such direction of travel and means for transversely adjusting said carbon-sheet guide to accommodate manifold forms of various widths. 90

2. In a device of the class described, the combination of a supporting frame; a carbon-sheet roll mounted on and at one side of 100 said frame; and a carbon-sheet guide mounted upon said frame and having a guiding surface forming an angle of forty-five degrees with reference to the axis of said roll; said guiding frame being adjustable in the direction of feeding a carbon-sheet from said roll. 105

3. In a device of the class described, the combination of a supporting frame; a carbon-sheet roll mounted on and at one side of 110 said frame; and a carbon-sheet guide mounted upon said frame, having one end free, and formed with a guiding surface forming an angle of forty-five degrees with reference to the axis of said roll, said carbon-sheet guide being adjustable to accommodate manifold forms of various widths. 115

4. In a device of the class described, the combination of a supporting frame; two carbon-sheet rolls respectively mounted on and at opposite sides of said frame, said rolls having parallel axes; and two carbon-sheet 120 guides having one end secured to one side of said frame and extending inwardly thereof and having its other end free whereby they may be inter-leaved with manifold forms; each of said guides being formed 125 with a guiding surface at an angle of forty-five degrees with reference to the axes of said rolls; the guiding surface on the respective carbon-sheet guides being right-angularly related to each other, said carbon-sheet 130

guides being adjustable toward and from each other to accommodate manifold forms of various widths.

5. In a device of the class described, the combination of a supporting frame; two carbon-sheet rolls respectively mounted on and at opposite sides of said frame, said rolls having parallel axes; and two carbon-sheet guides each having one end secured to one side of said frame and extending inwardly thereof and having its other end free whereby they may be interleaved with manifold

forms; each of said guides being formed with a guiding surface at an angle of forty-five degrees with reference to the axes of 15 said rolls; the guiding surface on the respective carbon-sheet guides being right-angularly related to each other; said carbon sheet guide being adjustable on said supporting frame in the direction of feed of 20 the carbon-sheet from said rolls.

Signed by me this 30th day of June, 1923.

EDWARD PHILIP KECK.
